Primary Examiner — Holly Baynham*Assistant Examiner* — Rhea Shields(74) *Attorney, Agent, or Firm* — Leason Ellis LLP(57) **CLAIM**

The ornamental design for a gift box, as shown and described.

DESCRIPTION

FIG. 1 is a side perspective view of a gift box showing my new design;

FIG. 2 is a top perspective view thereof;

FIG. 3 is a side perspective view thereof;

FIG. 4 is a side elevation view thereof; and,

FIG. 5 is a top plan view thereof.

In the drawings, the broken lines depict unclaimed subject matter only and form no part of the claimed design.
